UNITED STATES PATENT OFFICE.

CHARLES McCARTER, OF DECATUR, ILLINOIS, ASSIGNEE OF ONE-HALF TO CHARLES F. EVANS, OF DECATUR, ILLINOIS.

CAR-MOVER.

1,212,974.

Specification of Letters Patent. Patented Jan. 16, 1917.

Application filed April 25, 1916. Serial No. 93,380.

To all whom it may concern:

Be it known that I, CHARLES McCARTER, a citizen of the United States, and a resident of Decatur, in the county of Macon 5 and State of Illinois, have invented a new and Improved Car-Mover, of which the following is a full, clear, and exact description.

My invention relates to a contrivance 10 whereby cars can be easily moved on the tracks, and the object thereof is to provide a simple, inexpensive and efficient device for the purpose stated.

With the above and other objects in view, 15 the nature of which will more fully appear as the description proceeds, the invention consists in the novel construction, combination and arrangement of parts as herein fully described, illustrated and claimed.

20 In the accompanying drawings, forming part of the application, similar characters of reference indicate corresponding parts in all the views.

Figure 1 is a side elevation of my invention as applied to a car wheel to move a car; Fig. 2 is an end elevation, the actuating lever being shown in section; Fig. 3 is a fragmentary rear elevation similar to that shown in Fig. 2 but illustrating the contrivance in the position when the operating lever is moved upward or when the device is disengaged from the car wheel; Fig. 4 is a top plan view; Fig. 5 is a side elevation of the upper part of the device from the side opposite to what is shown in Fig. 1; Fig. 6 is a perspective view of the cam; Fig. 7 is a perspective view of the wheel and clamp which carries the cam; Fig. 8 is an elevation of a modified structure of the wheel clamp; 35 and Fig. 9 is an elevation of a further modification of the wheel clamp.

Referring to the drawings, 10 is the carriage truck or frame which has spaced flanged rollers 11 at the base for riding on 45 a rail 12 of the track. The carriage frame 10 at the top thereof has a bearing 13 disposed transversely of the frame for accommodating a double crank shaft 14, the two cranks 15 and 16 respectively being at the ends of the shaft and directed oppositely. The crank 16 has a socket for an

end of an operating lever 17 whereby the shaft 14 may be rocked in the bearing.

A link 18 connects the lug 19 of a cam or jaw 20 to the crank 15. The jaw is mounted 55 to revolve on a trunnion 21 provided at one end of a clamp 22. The clamp extends transversely of the frame and has at the other end a stationary jaw 23 whereat the clamp is suspended by a link 24 from a lug 26 extending from the crank 16. The link passes through a slot 25 in the lug. The clamp 22 is bent at the jaw 20 to clear the flange of the car wheel 27. The frame 10 has a boss 28 constituting a guide for the 65 clamp 22, the curvature of which is such as to maintain the clamp in close proximity to the car wheel when said clamp is moved by the rocking of the crank shaft 14.

The clamp 22 is balanced on a link 29 70 which is suspended from one end of a lever 30 fulcrumed between its ends on a cap of the bearing 13. The link 24 has a collar 31 adapted to engage the lug 26 when the clamp 22 is moved upwardly by the lever 30 whereby the upward movement of the fixed jaw is arrested, while the movable jaw is free to move; consequently the distance between the two jaws is increased and the device may be brought into engagement with the car 80 wheel. In releasing the lever 30, gravity brings the clamp into engagement with the sides of the car wheel.

By moving the actuating lever 17 down, the grip of the clamp on the wheel is increased, and, consequently, the car wheel is caused to move by the downward displacement of the actuating lever. As the actuating lever 17 is moved upward, the hold of the clamp on the car wheel is released, 85 due to the fact that the lug 26 is shorter than the crank 15, consequently, the distance between the fixed and movable jaws is increased during the initial upward movement of the lever 17. A reverse initial movement of the lever 17 shortens the distance 90 between the fixed and the movable jaw for the same reason and causes the clamp to grip the sides of the wheel.

It will be noted that the clamp 22 has 100 lugs 32 and 33 which are engaged by the links 24 and 29 respectively. The clamp has

similar lugs 32 and 33 on the opposite side which are used when the device is to be handled by a left-handed operator, in which case it is only necessary to reverse the 5 crank shaft and the clamp, the provision of the additional lugs referred to permitting this change.

In Fig. 8 the clamp 22' is shown provided with trunnions 21' at each end so that at 10 each end of the clamp a movable jaw may be provided, as shown in dotted line in said Fig. 8; in which case one of the jaws will be operated from the crank 15 and the other from the lug 26.

15 In Fig. 9 the clamp 22'' is shown provided with two fixed jaws 23'', the engagement of the wall with the said jaw being obtained by the unequal displacement of the two fixed jaws through the medium of the crank 15 20 and the lug 26. It will be noted that the operating lever 17 is outside of the track, consequently it may be operated without any hindrance where two cars are coupled, for there will be plenty of room to move the 25 lever due to the fact that said arm is outside of the track.

I claim:

1. A car mover comprising a frame, a lever fulcrumed on the frame, a clamp for 30 engaging the sides of a car wheel operable by the movement of the lever, and a boss extending from the frame for guiding the movement of the clamp.

2. A car mover comprising a frame, 35 rollers therefor for riding on a rail, a double crank shaft mounted to rock in the frame, the two cranks being directed oppositely, one of said cranks having a socket, a lever engaging said socket whereby the shaft may 40 be rocked, a lug extending from said socket having crank in a direction parallel to the second crank, said lug being shorter than said second crank, and a clamp suspended from said lug and second crank to engage or 45 disengage the sides of a car wheel when said shaft is rocked.

3. A car mover comprising a frame, 50 rollers therefor for riding on a rail, a bearing at the top of the frame disposed transversely thereof, a double crank shaft in said bearing, the two cranks being disposed oppositely, one of said cranks having a socket, a lever engaging said socket, a lug extending from said crank having a socket in the 55 same direction with the second crank, said lug being of a shorter length than said second crank, a clamp for engaging the sides of a car wheel, links connecting said clamp to the lug and said second crank, and means 60 for moving the clamp between the lug and the second crank.

4. A car mover comprising a frame, 65 rollers therefor for riding on a rail, a clamp for engaging the sides of a car wheel, a lever

fulcrumed on the frame, and means for connecting the lever to the ends of the clamp so that one end of the clamp has a greater movement than the other during the movement of the lever, whereby said clamp may be caused to engage or disengage the car 70 wheel.

5. A car mover comprising a frame, a movable clamp having a fixed jaw and a movable jaw for engaging the sides of a car wheel, a rocking shaft on the frame engaging the fixed and movable jaws of the clamp, and means for actuating the shaft whereby the jaws are caused to engage or disengage the car wheel, said clamp having means for 75 guiding the movement of the clamp. 80

6. A car mover comprising a frame, rollers therefor for riding on a rail, a clamp having a fixed jaw at one end and a trunnion at the other parallel to the fixed jaw, a jaw on the trunnion, a rocking shaft on the 85 frame, a link connecting the shaft to the movable jaw, a lug shorter than the crank connecting the shaft to the fixed jaw, means for rocking the shaft whereby the clamp is actuated, and a boss on the frame for guiding the movement of the clamp when the 90 same is actuated.

7. A car mover comprising a frame, rollers therefor for riding on a rail, a rocking shaft disposed transversely of the frame, 95 oppositely disposed cranks associated with the shaft, one of said cranks having a socket, a lever engaging the socket, a clamp having a fixed jaw and a movable jaw suspended from the frame, a lug extending from the 100 crank having a socket, a link connecting said lug to the fixed jaw of the clamp, means on said link limiting the movement of the fixed jaw to and from said lug, a link connecting the second crank to the movable jaw 105 of the clamp, and means for actuating the clamp on its suspension from the frame.

8. A car mover comprising a frame, 110 rollers therefor for riding on a rail, a gravitationally-operable clamp suspended from the frame transversely thereof, a rocking shaft on the frame, means for connecting the clamp loosely to the rocking shaft, and means for rocking the shaft, said connecting 115 means including means for causing an unequal displacement of the clamp when the rocking shaft is operated.

9. A car mover comprising a frame, 120 rollers therefor for riding on a rail, a clamp having jaws at the ends thereof for engaging the sides of a car wheel, a lever of the first class fulcrumed on the frame, a link connecting one end of said lever to the clamp between the ends thereof so that the clamp is balanced on said link, operating means on 125 the frame, and means connecting the operating means to the ends of the clamp so that the said ends may be displaced unequally by

the operating means, said connecting means including means whereby the ends of the clamp may be displaced unequally by the lever of the first class.

5. 10. A car mover comprising a frame, rollers therefor for riding on a rail, a clamp having jaws at the ends thereof for engaging the sides of a car wheel, an actuating

lever on the frame, motion-transmission means connecting the lever to the jaws of the clamp for unequally displacing the same, and means for bringing the jaws of the clamp into engagement with a car wheel independently of the operating lever. 10
